UNITED STATES PATENT OFFICE.

JOSEPH T. SCHLESINGER, OF NEW YORK, N. Y., ASSIGNOR TO UTILITY APPLIANCE CORPORATION, A CORPORATION OF DELAWARE.

DOOR LOCK FOR ELEVATORS.

Application filed January 17, 1921. Serial No. 437,925.

To all whom it may concern:

Be it known that I, JOSEPH T. SCHLESINGER, a citizen of Hungary, and a resident of the city of New York, in the county of 5 New York and State of New York, have invented certain new and useful Improvements in Door Locks for Elevators, of which the following is a specification.

The present invention relates to improvements in door-locks for elevators, and more particularly to a door-lock controlling, by the position of the door, the elevator motor mechanism.

The main object of the invention is to 15 provide a simple and efficient door-actuated control mechanism for elevators, involving electric features.

Another object of the invention is to produce a simple and inexpensive door lock for 20 elevators, including a stationary element on the door frame and a sliding element on the door, said stationary and sliding elements constituting a switch inserted in the control circuit of the motor, so that the elevator cannot 25 be started unless the door is in its fully closed and locked position.

Another object of the invention is to produce a door lock of the type mentioned, which is applicable both to swinging and 30 sliding doors.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion 35 of the several parts and details of construction within the scope of the appended claims, without departing from the spirit or sacrificing any of the advantages of the invention.

One of the many possible embodiments of the invention is illustrated in the accompanying drawings, in which:—

Figure 1 is a front elevation, partly in section, of a door-lock constructed in accordance with the present invention; Fig. 2 is a side elevation thereof; and Fig. 3 is a front elevation of a portion of a modified construction.

Referring now first to Figs. 1 and 2 of the 55 drawings, the numeral 10 indicates a casing

of any suitable construction and adapted to be fastened to the door frame of an elevator, for instance by screws passing through lugs 11 thereon. This casing is provided with a detachable front plate 12, not shown in Fig. 1 of the drawings. In the bottom 60 13 of the casing is formed an opening 14, through which the locking bolt, carried by the elevator door, may be projected into the casing. The bottom 13 includes two slanting portions 15, which converge toward the opening 14, for a purpose hereinafter to be described. From the back plate 16 of the casing extends outwards a projection 17, having an inclined face 18 slanting toward 65 the said opening. The purpose of this arrangement will appear hereinafter.

Within the casing are mounted two insulating blocks 19, one on each side of the opening 14, and to these blocks are fastened, for instance by screws 20, metallic contact plates 21, forming part of a switch. The contact plates are, preferably, made in the form of blade-springs, extending substantially vertically, their lower ends being free and in operative relation to the opening 14 in the casing bottom. The contact plates are inserted into the motor control circuit of the elevator, the conductors leading to the screws 20, in contact with the plates 21.

On the elevator door is mounted a vertically extending locking slide bar 22, movable in guides 23, the latter being securely fastened to the door. The slide bar is provided with an operating handle 24, preferably hollow and containing a spring 25, bearing against the handle and against a fixed stop 26 on the door. This stop extends into the handle, thus acting as an additional guide for the slide bar. The spring 90 has a tendency to project the slide bar through the opening 14 of the casing 10, its upward movement being limited by a washer 27 on said bar and abutting against the underface of one of the guides 23. The slide bar 22 is, preferably, tubular and carries at its upper end a head 28, on which is mounted an insulating block 29, fitting the opening 14 in the casing bottom. On this block is mounted a metallic plug 30, adapted to be inserted between the contact plates 21. The plug is provided with an anti-friction ball 31, adapted to co-operate with the slanting portions 15 or the inclined face 18 of the projection 17, as the case may be.

The operation of this device is as follows: When the elevator door is in its closed position, the slide bar 22 projects into the casing 10, its plug 30 bridging the gap between 5 the contact plates 21 and thereby completing the motor control circuit. The insulating block 29 is projected by the spring 25 into the casing, holding the door in locked position. The slide bar has thus a two-fold 10 function, to wit: It, first, serves as a locking bolt and, second, it performs the function of a switch plug, that is to say it constitutes the movable element of a switch. Assuming that the elevator door is of the 15 sliding type and moves in the direction of the arrow marked X in Fig. 1 of the drawings toward opening position, it is obvious that, in order to open the door, first the slide bar must be shifted downwards in the 20 direction of its longitudinal axis until it is completely disengaged from the casing 10, whereafter the door may be moved in the direction of the arrow mentioned. When the bar is thus retracted from the casing, 25 the motor control circuit is opened and the elevator cannot be started until the door is again closed and securely locked. In shifting the door toward closing position, the anti-friction ball 31 is brought into contact 30 with one of the slanting bottom portions 15 of the casing, which acts thus as a striker, the spring 25 being thereby compressed, shifting the slide bar upwards as soon as it is brought into alignment with 35 the opening 14 in the casing bottom, whereby by the motor control circuit is completed. If the door is movable in a direction opposite to the arrow X, the opposite slanting portion 15 of the casing bottom will act as 40 a striker, and, if the door is a swinging one, the projection 17 will perform this function.

The modification shown in Fig. 3 of the drawings differs from the one above described in that an anti-friction roller 32 is 45 mounted upon the insulating block 29, instead of the ball 31 above referred to.

What I claim is:—

1. In a door lock for elevators, the combination with a casing having an opening

in its bottom mounted upon the door frame, 50 of a locking slide bar on the elevator door, means for projecting said bar through said opening into said casing, spaced apart contact plates within said casing in the motor control circuit of the elevator, and a metallic plug carried by said slide bar for bridging the gap between said contact plates. 55

2. In a door lock for elevators, the combination with a casing having an opening 60 in its bottom mounted upon the door frame, of a locking slide bar on the elevator door, means for projecting said bar through said opening into said casing, and a switch in the motor control circuit of the elevator, part of said switch being carried by said 65 casing and part by said locking bar.

3. A door lock for elevators according to claim 1, comprising a striker on said casing, and anti-friction means co-operating with said striker mounted upon said slide 70 bar. 75

4. A door lock for elevators according to claim 2, comprising a striker on said casing, and anti-friction means co-operating with said striker mounted upon said slide 75 bar.

5. In a door lock for elevators according to claim 1, said slide bar including a hollow handle portion and said projecting means being mounted within said handle portion. 80

6. In a door lock according to claim 2, said slide bar including a hollow handle portion and said projecting means being mounted within said handle portion. 85

7. A door lock according to claim 1, comprising co-acting means on the elevator door and said slide bar for limiting the extent of projection of said slide bar into said casing. 90

8. A door lock according to claim 2, comprising co-acting means on the elevator door and said slide bar for limiting the extent of projection of said slide bar into said casing. 95

Signed at New York, in the county of New York and State of New York, this 31st day of December, A. D. 1920.

JOSEPH T. SCHLESINGER.
